Inventor -

George W. Bruderick

UNITED STATES PATENT OFFICE

121,063

DESIGN FOR AN AUTOMOBILE SIGNAL LAMP

George W. Bruderick, Detroit, Mich.

Application October 31, 1939, Serial No. 87,793

Term of patent 7 years

To all whom it may concern:

Be it known that I, George W. Bruderick, a citizen of the United States, residing at Detroit, in the county of Wayne, and State of Michigan, have invented a new, original, and ornamental Design for an Automobile Signal Lamp, of which the following is a specification, reference being had to the accompanying drawing, forming a part thereof, in which:

Figure 1 is a front elevational view of an automobile signal lamp, showing my new design; Figure 2 is a side elevational view; and Figure 3 is a top plan view thereof.

I claim:

The ornamental design for an automobile signal lamp, as shown.

GEORGE W. BRUDERICK.
